UNITED STATES PATENT OFFICE.

MOSE FUCHS, OF BAKER, OREGON.

ADJUSTABLE GOLF-TEE BOARD.

1,173,792.

Specification of Letters Patent. Patented Feb. 29, 1916.

Application filed October 9, 1915. Serial No. 55,089.

To all whom it may concern:

Be it known that I, Mose Fuchs, a citizen of the United States, and a resident of Baker, in the county of Baker and State 5 of Oregon, have invented a new and Improved Adjustable Golf-Tee Board, of which the following is a full, clear, and exact description.

An object of my invention is to provide 10 a golf-tee board having tee elements movable to provide separate individual tees either of which may be positioned for use, and thus provide a tee at different elevations above the board to meet the ideas of 15 individual players.

A further object of the invention is to provide a revolvably mounted golf tee, whereby by the tee will yield and turn in the direction of a blow delivered against the ball in 20 driving the ball from the tee.

The invention will be particularly explained in the following description of the preferred embodiment as illustrated.

Reference is to be had to the accompanying 25 drawings forming a part of this specification in which similar reference characters indicate corresponding parts in all the views.

Figure 1 is a perspective view of a golf- 30 tee board embodying my invention; Fig. 2 is a partial plan view; and Fig. 3 is a partial longitudinal vertical section.

In carrying out my invention in practice, in accordance with the illustrated embodiment, a board 10 of suitable dimensions is 35 provided and a golf tee, designated generally by the numeral 11, revolvably mounted on the board in a vertical slot or opening 12, therein, to turn in the vertical plane, a 40 transverse pin 14, or the like serving as the axis.

The body 13, of the tee is preferably in 45 the form of a disk through which the pin 14, passes at the center. On the said disk at the periphery at intervals therearound, radially disposed individual tees are formed indicated respectively by the numerals 15, 16, 17, there being three such individual tees in the present instance. The ends of the 50 individual tees present faces transvers to the plane of rotation either of which seats is adapted to receive a golf ball A when a particular individual tee is positioned at the top of the board 10.

55 The individual tees project varying dis-

tances from the axis of rotation so that the ball may be supported at different elevations above the board 10, as may be desired by the individual player. It will be seen that when the ball A is driven from 60 either one of the individual tees, 15, 16, 17, the tee as a whole will yield and turn in the direction of the blow thereby reducing the possibility of injury to the tee, and permitting an unretarded release of the ball. 65 Moreover, the tee will be less liable to injury by persons walking over the field since it will yield and turn upon a foot contacting therewith and therefore will be less liable to be crushed.

70 It will be seen that a single tee board provides a variety of tees to suit the wishes of individual players and in a manner to enable a particular tee to be instantly positioned for use.

Having thus described my invention I claim as new and desire to secure by Letters Patent:

1. A golf tee mounted to turn and having 80 seats thereon for a golf ball, the seats being disposed at different distances from the axis of the tee.

2. A golf-tee board and a tee revolvably mounted on the board and having seats for a golf ball at the edge of the tee at different 85 distances from the axis.

3. A golf-tee board having a depression 90 in its upper surface and a tee mounted to turn in the said depression in approximately a vertical plane, said tee having a plurality 95 of seats at different points therearound, the surfaces of the seats being transverse to the plane of rotation of the tee and at different distances from the axis of the tee and optionally turnable with the tee, to position either seat projecting above the top of the board.

4. A golf-tee board and a tee mounted on the board to turn in a vertical plane, said tee including a plurality of radially disposed individual tees projecting at different 100 distances from the axis.

In testimony whereof I have signed my name to this specification in the presence of two subscribing witnesses.

MOSE FUCHS.
